POWER SUPPLY REGULATOR

Richard Projain, Syosset, and Robert Gold, St. James, N.Y., assignors to Lamda Electronics Corporation, Huntington, N.Y.

Filed Mar. 4, 1971, Ser. No. 121,228

Term of patent 14 years

Int. Cl. D13—02

U.S. Cl. D26—15

FIG. 1

FIG. 2

FIG. 3

FIG. 4

FIG. 5

FIG. 1 is a perspective view of a power supply regulator embodying our new design showing the top, one side and left end thereof;

FIG. 2 is a top plan view of the power supply regulator of FIG. 1;

FIG. 3 is a side elevational view of the power supply regulator of FIG. 1 showing the opposite side thereof;

FIG. 4 is an end elevational view of the new design showing the right end thereof; and

FIG. 5 is a bottom plan view of our new power supply regulator design.

We claim:

The ornamental design for a power supply regulator, as shown.
